UNITED STATES PATENT OFFICE.

SARAH L. MURRAY, OF LOS ANGELES, CALIFORNIA.

COMBINATION DESK AND TABLE.

Application filed April 6, 1926. Serial No. 100,050.

This invention relates to improvements in combination desks and tables.

An object of the invention is to provide a device which is primarily adapted to be used by invalids and persons reclining in bed or on a couch for supporting things before them. The device is particularly adapted to be used by invalids for supporting dishes and the like so as to serve as a table, and is capable of being adjusted so as to support books before them in a proper inclined position so as to facilitate reading. The device can also be used by other people, as, for example, students who wish to read or study while in a reclining position.

With the foregoing and other objects in view which will be made manifest in the following detailed description and specifically pointed out in the appended claims, reference is had to the accompanying drawings for an illustrative embodiment of the invention, wherein:

Figure 1 is a perspective view of the device showing the device adjusted so as to form a table,

Fig. 2 is a view similar to Fig. 1, showing the device adjusted to form an inclined support or desk.

Fig. 3 is a vertical section taken substantially on the line 3—3 of Fig. 1, and

Fig. 4 is a vertical section taken substantially on the line 4—4 of Fig. 2.

Referring to the accompanying drawings wherein similar reference characters designate similar parts throughout, the device consists of two end supporting members 10 and 11, shown as formed of two rectangular sections of material which may be wood or any other material. The exact form of the end supporting members may be varied and, of course, is immaterial. The end supporting members 10 and 11 are held together in proper spaced relation by a forward transverse member 12 which is rigidly secured between the opposed faces of the end supporting members in an inclined position, so as to present an upwardly and forwardly inclined upper surface. As clearly shown in Fig. 3, the uppermost edge of the forward transverse member 12 is preferably so arranged as to be below the upper edges of the end supporting members 10 and 11. A rear transverse member 13 connects the rearward ends of the end supporting members 10 and 11 and cooperates with the transverse mem-

ber 12 to hold them in proper spaced relation. The under edge of the rearward transverse member 13 may be concaved or curved upwardly, as indicated at 14, if desired. A 60 table top 15 is provided which is pivoted to the end supporting members 10 and 11 as by pintles 16 extending through the end supporting members and into the end edges of the table top 15, thus pivoting the table 65 top 15 intermediate its forward and rear edges.

Adjacent the back of the table top 15 there are fastened suitable brackets 17 to which are pivoted links 18 having slots 19 formed 70 therein. Upon the inside faces of the end supporting members 10 and 11 there are fixed studs 20, which are threaded and which extend through the slots 19 in the links 18 so that the links 18 can slide thereon. 75 Wing nuts 21 are threaded onto the studs 20 and are capable of being screwed down against the links 18. In the position shown in Fig. 1, the table top 15 is lowered into horizontal position forming a substantially 80 level table upon which articles may rest. When the device is in this position, it can be used by invalids to support dishes, etc., for their meals by placing the device over the trunk or the legs of the invalid. It will be 85 understood that the end supporting members 10 and 11 are positioned upon the outside of the legs of the invalid or other person in reclining position and that the articles may be supported on the table top 15, permitting 90 him to easily reach any article supported thereon.

As shown in Fig. 2, the table top 15 is raised to an inclined position, which is permitted by loosening the wing nuts 21 and 95 swinging the table top upon the pintles 16. After the table top has reached the desired inclined position, it can be frictionally held in place by tightening the wing nuts 21. In this position it cooperates with the forward transverse member 12 to support books, papers, magazines and the like in proper position to facilitate reading. The inclined transverse member 12 is so arranged preferably to have its upper surface tangent 100 to a circle about the pintles 16, so that when the table top 15 is raised into inclined position, its forward edge may fit against the transverse member 12 and prevent articles resting upon the ledge provided by the transverse member 12 from falling therebetween.

From the above it will be readily appre-

ciated that an improved combination desk and table is provided, which can be used to support articles either in a horizontal or inclined position, and which is especially adapted to be used by invalids or other persons in reclining positions.

It will be understood that various changes in the detail of construction may be made without departing from the spirit or scope 10 of the invention as defined by the appended claims.

I claim:

1. A combination desk and table comprising a pair of end supporting members, a forward transverse member presenting an inclined upper surface connecting the forward ends of said end supporting members, a rear transverse member connecting the rear ends of said supporting members, a table top pivoted to said end supporting members slotted links pivoted to said table top, means providing studs upon said end supporting members slidably extending into the slots in said links, and wing nuts threaded onto said 25 studs adapted to engage said links for holding the table top in adjusted position.

2. A combination desk and table comprising

ing a pair of end supporting members, a forward transverse member in the form of a shelf rigidly secured between the opposed 30 faces of the end supporting members in an inclined position with its uppermost edge below the upper edges of the end supporting members, a rear transverse member connecting the rearward ends of the end supporting members and cooperating with the transverse member to hold the supporting members in proper spaced relation, a table top fitting loosely between the upper ends of the end supporting members and pivoted in 40 place, the pivots being near the forward part of the top and the forward edge of the top swinging loosely inside and above the transverse member, brackets secured to the lower face of the top near its rear edge and near 45 its ends, slotted links connected to the brackets, studs fixed to project inwardly from the end supporting members through the slots in the links, and nuts for holding the links in adjusted positions upon the studs to hold the 50 table top in adjusted position.

In testimony whereof I have signed my name to this specification.

SARAH L. MURRAY.
